(57) **CLAIM**

The ornamental design for a shop chair, as shown and described.

DESCRIPTION

FIG. 1 is a top, left, front perspective view of a shop chair, shown with a lower tray;

FIG. 2 is a bottom, left, rear perspective view of a shop chair without a lower tray;

FIG. 3 is a left side view thereof;

FIG. 4 is a right side view thereof;

FIG. 5 is a front view thereof;

FIG. 6 is a rear view thereof;

FIG. 7 is a top plan view thereof showing the shop chair with the seat, outer ring, fasteners, outer leg bracket and caster wheels shown in broken lines; and,

FIG. 8 is a bottom plan view thereof.

The broken lines shown in the drawings depict portions of the article that form no part of the claimed design.

1 Claim, 8 Drawing Sheets
